UNITED STATES PATENT OFFICE

2,526,979

AUTOMATIC SCREEN DOOR HOOK

John E. Tomlinson, Los Angeles, Calif.

Application June 27, 1947, Serial No. 757,399

1 Claim. (Cl. 292—135)

1

The present invention relates to automatic screen door hooks and it consists in the combinations, constructions and arrangements of parts herein described and claimed.

It is an object of the invention to provide an automatic latch for screen doors or the like.

A further object of the invention is the provision of a simple, compact, inexpensive and efficient closure latch.

Another object of the invention is the provision, in a latch, of a simple and effective means for unlatching the same.

Other and further objects of the invention will become apparent from a reading of the following specification taken in conjunction with the drawings, in which:

Figure 1 is an elevational view of an embodiment of the invention,

Figure 2 is a plan view, partly in section, taken along line 2—2 of Figure 1 in the direction of the arrows,

Figure 3 is an elevational sectional view taken along line 3—3 of Figure 2, and

Figure 4 is an exploded perspective view illustrating the method of assembly of the invention.

Generally, the invention comprises a latch consisting of a hook pivotally carried in a frame member mounted in a door or the like and adapted to engage a detent carried by the jamb of a door. Upon the outer side of the door and carried by the frame is a slidably mounted detent having an outwardly extending operating button and adapted to engage at its inner end a cammed portion of the hook whereby, when the button is pressed, the hook will be raised to disengage from the detent carried by the jamb.

Referring more particularly to the drawings, there is shown therein a latch having an inner plate member 10 and an outer plate member 11 adapted to be mounted at either side of an opening 12 formed in a door 13. The plate 10 has integrally formed therein a pair of inwardly extending ears 14 which carry an axle 15 therebetween upon which is pivotally mounted a hook 16 which extends inwardly and is provided with a notch 17 adjacent its inner end and which is adapted to engage with a detent 18 affixed to a jamb 19 as, for example, by a screw 20.

The inner end of the hook 16 is provided with a downwardly extending cammed end 21. A pair of bolts 22 are adapted to interconnect the plates 10 and 11 and act as guides for a dog 24 having a pair of diametrically opposed grooves

2

25 formed longitudinally therein. The bolts 22 are adapted to engage in the grooves 25. Integrally formed with the dog 24 is an operating button 26.

5 In operation, it will be apparent that when the door is closed either by hand operation or by the operation of a spring in the conventional manner, that the hook 16, due to its angular inner face 27, will ride over the detent 18 and fall into position thereover in such manner that the detent 18 will lie within the notch 17, thereby effectively latching the door. When it is desired to unlatch the door, the button 26 is pressed inwardly of the door 13 thereby causing the dog 24 to move against the cammed portion 21 of the hook 16 and thereby causing the hook 16 to be raised at its inner end thereby becoming disengaged from the detent 18 whereupon the door may be opened in the conventional manner.

10 While but one form of the invention has been shown and described herein, it will be readily apparent to those skilled in the art that many minor modifications may be made without departing from the spirit of the invention or the 15 scope of the appended claim.

20 What is claimed is:

A device of the character described comprising a pair of plates mounted at either side of an aperture in a door, a pair of bolts interconnecting the plates, a hook pivotally mounted in the inner plate and having a cammed rear end, a dog having a pair of grooves adapted to slidably engage the bolts between the plates, a button formed integrally with the dog and protruding through the outer plate and adapted when pressed inwardly to force the dog into engagement with the rear end of the hook to thereby lift the outer end of the hook against the action of gravity.

JOHN E. TOMLINSON.
